UNITED STATES PATENT OFFICE.

CLYDE C. BRANT, OF LOS ANGELES, CALIFORNIA, ASSIGNOR TO A. L. NEW, OF OCEAN PARK, CALIFORNIA.

DESIGN FOR A JAR.

Application filed November 16, 1925. Serial No. 15,430. Term of patent 14 years.

To all whom it may concern:

Be it known that I, CLYDE C. BRANT, a citizen of the United States, residing at Los Angeles, in the county of Los Angeles and State of California, have invented a new, original, and ornamental Design for a Jar, of which the following is a specification, reference being had to the accompanying drawing, forming a part thereof.

Fig. 2 is a side elevation thereof.

Fig. 3 is another side elevation looking from the right or left of Figs. 1 and 2.

Fig. 4 is a longitudinal sectional view on line α^4 , Fig. 3.

Fig. 5 is a transverse sectional view on line α^5 , Fig. 3.

Fig. 6 is a transverse sectional view on line α^6 , Fig. 4.

Fig. 7 is a bottom view.

Fig. 8 is a transverse section on line α^8 , Fig. 3.

I claim:

The ornamental design for a jar as shown.

Signed at Los Angeles, in the county of Los Angeles, and State of California, this 11th day of November, 1925.

CLYDE C. BRANT.
